UNITED STATES PATENT OFFICE.

ROBERT KACH, OF PORTLAND, OREGON.

GAS MIXER.

Application filed April 1, 1921. Serial No. 457,625.

To all whom it may concern:

Be it known that I, ROBERT KACH, a citizen of the United States of America, and resident of Portland, in the county of Multnomah, in the State of Oregon, have invented certain new and useful Gas Mixers, of which the following is a specification, reference being had to the accompanying drawing.

10 My invention relates to gas mixers for internal combustion engines, and has for its object the production of such a mixer in which special means are provided for the breaking up and mixing of gasoline without 15 interruption of its volume of flow.

It is recognized in the art that much of the gasoline that is now being used is of a low grade, and that the charge thereof in passing from the carburetor to the engine 20 contains, particularly in cold weather, particles of fuel that have not been properly broken up and mixed. The result is incomplete combustion, with attendant evils, which, though well understood in the art, it 25 has not been practicable to remedy to a satisfactory degree, and by means that have proved to be altogether practicable and efficient.

In devices for the purposes indicated, it 30 is important that they be at the same time efficient for breaking up and mixing of all particles of the fuel, and that they operate without checking the volume of flow thereof. In both of these respects the efficiency of my 35 mixer has been amply demonstrated.

What constitutes my invention is herein-after specified in detail and is succinctly set forth in the appended claims.

In the accompanying drawing,

40 Figure I is a top plan view of an engine intake manifold and carburetor discharge pipe, showing my mixer chamber, with cover removed, introduced into the pipe between the carburetor and the manifold.

45 Figure II is a side elevation, partly in vertical section, of the subject matter of Figure I, and with a suitable form of cover for the mixer chamber, in section and in place.

50 Figure III is a side elevation of the last of a series of mixer baffle-plates, detached.

Figure IV is a similar view of the intermediate baffle-plate of said series, detached.

55 Figure V is a similar view of the primary baffle-plate of said series, detached.

Referring to the numerals on the drawing,

1 indicates an example of the intake manifold of an engine, not shown, 2 the plate of a carburetor, not shown, and 3 a pipe of suitable capacity, that operatively unites the members 1 and 2, in any usual manner of assemblage, such, for example, as the mutual relationship shown in the drawing.

60 In the body of the pipe 3, or at any convenient point of location between the carburetor and the manifold, is provided a mixer chamber 4, that is preferably of substantially rectangular shape in cross-section, and of a calculated greater capacity than that of the pipe 3 into which it is introduced.

65 The chamber 4 is provided, in a wall thereof preferably on top, with an opening 5, that is, in service, tightly closed by a suitable cover, preferably that shown in the drawing and indicated by the numeral 6. The 70 cover, fitting within the frame of the opening 5, is provided with suitable means, for example, lateral flanges 7 for securing the cover in place. Through apertures in said flanges are introduced tap-screws 8, that are 75 threaded into screw-holes 8', provided for them in the frame of the opening 5.

80 Within the chamber 4 is assembled a series comprising a plurality, say three, of metallic baffle-plates, 9, 10, and 11. The 85 plate 9, of the series illustrated, is termed the primary baffle-plate; the plate 10, is termed an intermediate baffle-plate and the plate 11 the last baffle-plate, they being so designated to indicate their relative order of 90 arrangement towards the carburetor, whose location is indicated by the carburetor-plate 2.

85 The several plates 9, 10, and 11, snugly fit the interior of the chamber 4, filling also, respectively, the spaces provided for them 95 between the bottom 12, of the chamber 4 and the inside of its cover member 6, which serves, besides closing the chamber 4, to confine said plates in place therein. The element 6 is designated a cover member, because it may comprise more than the single plate illustrated, as the present preferred form. The plates 9 and 11 are aligned at top and bottom, respectively, and are firmly mounted within the interior of the chamber 100

105 4 as by buttresses 15 and 16, there being an opposing pair of buttresses in the top and bottom walls, respectively, of the chamber. The plates 9 and 11 are provided, respectively, with lateral flanges 17 and 18, 110 whose width is such that, when set in place within the chamber 4, as shown in Figure

I, they afford, between their opposing edges, just enough space to admit between them, the intermediate plate 10, which is a flat plate, its opposite sides being flush, without flanges.

It was specified above that the capacity of the chamber 4 is calculated so as to exceed that of the pipe 3 into which it is introduced. The difference in the relative 10 capacities of said members is such as to permit of the accommodation in the several plates 9, 10, and 11, of series of apertures, the sum of the areas of each series of apertures being substantially equal to the cross-sectional area of the pipe 3. By the means 15 just described, provision is made for the passage of gas through the pipe 3 without any interruption of the volume of its flow by reason of the presence of such plates, as, 20 for instance, those exemplified in the plates 9, 10, and 11.

Moreover, by providing said plates severally with a different number or arrangement of apertures, with variation of both 25 number and arrangement, the gas, in passing through the plates 9, 10 and 11, derives therefrom an increased breaking up and mixing effect.

The variation of the number of apertures 30 in the several baffle-plates of a series effects a distinctly staggered relative arrangement of those apertures in successive assembled plates, whereby a new and useful mixing effect upon the gas in flowing through them 35 is gained.

In the series composed of three baffle-plates, as illustrated, the plate 9 is, by preference, provided with a group of four apertures 20, the plate 10 with a group of nine apertures 21, and the plate 11 with a group 40 of sixteen apertures 22. It is repeated that each of said groups of apertures is equal in area to the cross-sectional area of the pipe 3, whereby varying deflection of the flow 45 of gas through them successively is effected without interruption of the volume of its flow.

The operation of my mixer will be, it is believed, apparent to one skilled in the art, 50 without further description thereof.

What I claim is:

1. A gas mixer of the kind specified, comprising the combination with a pipe, and a

mixer chamber therein having, as set forth, a relatively greater capacity than the pipe, 55 of a series of baffle-plates in said chamber each plate having a group of apertures in it, the individual apertures of each plate being disaligned from those of the next adjacent plates, the area of each group being substantially equal to the cross-sectional area 60 of the pipe.

2. A gas mixer of the kind specified, comprising the combination with a pipe, and a mixer chamber therein having, as set forth, a relatively greater capacity than the pipe, 65 of a series of baffle-plates in said chamber each plate having a group of apertures in it, the area of each group being substantially equal to the cross-sectional area of the pipe, 70 and each group being composed of a greater number than the group of a preceding plate of the series.

3. A gas mixer of the kind specified, comprising the combination with a pipe, and a mixer chamber therein having, as set forth, a relatively greater capacity than the pipe, and having an opening in a wall thereof, of a series of apertured baffle-plates firmly mounted within said chamber, a cover member within said opening and applied against the edges of said plates to hold them in place, and means for fastening the cover member in place and closing said opening. 75

4. A gas mixer of the kind specified, comprising the combination with a pipe, and a mixer chamber therein, having, as set forth, a relatively greater capacity than the pipe, and having an opening in a wall thereof, of a series of apertured baffle-plates firmly mounted within said chamber, a cover member fitting said opening and applied against the edges of said plates to hold them in place, and means for fastening the cover member in place and closing said opening, 80 90 a portion of said plates of the series having lateral flanges being adapted to confine the remainder of the series in place, substantially as set forth.

In testimony whereof, I have hereunto set my hand in the presence of two subscribing witnesses.

ROBERT KACH.
